DESIGN FOR AN ASH RECEIVER

Fred Leo Burnell, Yonkers, N. Y., assignor to American Telephone and Telegraph Company, a corporation of New York

Application April 13, 1938, Serial No. 76,487

Term of patent 14 years

To all whom it may concern:

Be it known that I, Fred Leo Burnell, a citizen of the United States, residing at Yonkers, in the county of Westchester, State of New York, have invented a new, original, and ornamental Design for an Ash Receiver, of which the following is a specification, reference being had to the accompanying drawing, forming a part thereof.

The figure is a perspective view of an ash
receiver, showing my new design.

I claim:

The ornamental design for an ash receiver,
as shown.

FRED LEO BURNELL.
